APPARATUS FOR LIQUID TREATMENT
OF STRANDSHenry J. McDermott, Prospect Park, Pa., assignor
to American Viscose Corporation, Wilmington,
Del., a corporation of Delaware.

Application April 6, 1945, Serial No. 586,993

10 Claims. (CL. 68—205)

1

The present invention relates to apparatus for the liquid treatment of strands and is particularly concerned with the type of apparatus in which the strand proceeds in a generally helical path about one or more rotors.

Heretofore, there has been no satisfactory answer to the problems involved in maintaining treating liquids separate when it is desired to apply two or more such liquids of different composition in succession to axially displaced portions of the helix. One suggestion has been to provide an annular baffle or ridge to separate the different treating zones of the rotor or rotors. However, this has the disadvantage of requiring the helix to be carefully positioned so that none of its convolutions cross the baffle or ridge as the strand proceeds from one treating zone to the adjacent zone following. Failure to predetermine the path of the windings in the helix so that they will not make contact with the ridge results in stretching or distortion of the strand either continuously or at intervals thereon depending upon the nature of contact.

It is the chief object of the present invention to provide an improved arrangement for minimizing intermingling of different liquids in adjacent treating zones of the rotor or rotors while assuring that the effective diameter of the strand carrying periphery of the rotor or rotors is not substantially changed between adjacent zones of such rotors. In accordance with the present invention, this is accomplished by providing a plurality of inclined notches or recesses arranged in a band about the rotor where separation of the liquids is required. Ancillary objects and advantages of the invention will be apparent from the drawing and description thereof hereinafter.

In the drawing which is illustrative of the invention,

Figure 1 is perspective view with parts in section of an apparatus embodying the present invention.

Figure 2 is an end elevation of the embodiment of Figure 1.

Figure 3 is a side elevation of one of the rotors of this embodiment.

Figure 4 is an enlarged view, in perspective of a portion of the surface of the rotor showing a preferred form of recess, and

Figure 5 is a perspective view illustrating a modified form of drip pan adapted to be associated with the rotors.

As shown generally in Figures 1 and 2, the strand 2 proceeds around a pair of vertically spaced rotors 3 and 4 which are mounted on

2

shafts 5 and 6 respectively for rotation. The rotors may be freely rotatable or either one or both may be driven. Preferably, the upper one is driven. The rotors 3 and 4 may be cylindrical and mounted on slightly canted or askew axes of rotation or they may be frusto-conical, preferably tapering to a smaller diameter at the unsupported ends thereof, in which latter case they may be mounted on substantially parallel axes. Preferably the strand is led to the rotors near their supported ends so it is discharged from the unsupported ends. Different liquids may be supplied to spaced zones of the upper rotor by means of the feed pipes 7 and 8 respectively and to the lower rotor by the feed pipes 7a and 8a respectively. If desired, pipes 7a and 8a may be omitted and the lower rotor may derive its liquid from the upper through the agency of the courses of the strand extending between them or, in addition, by dripping action from the upper rotor. Each zone of each rotor may be provided with a separate drip pan. As shown, the treatment zone of the upper rotor near its supported end operates within a drip pan 9 which may have a discharge connection 10. The lower rotor is provided with two generally concentrically arranged drip pans 11 and 12 respectively, the former for the zone toward the supported end of the rotor and the latter toward the unsupported end thereof. Preferably, the drip pans are spaced with their internal surfaces in close proximity to the windings about the rotors but without touching them and, as shown, it is desirable that the bottoms of the pans slope downwardly toward the end of the rotor or rotors from which the strand proceeds, this being the supported end as shown. This construction assists counter-current flow. The liquid feeding pipes 7 and 8, in such event, are preferably positioned toward the strand discharge ends of the respective treating zones of the rotors. Also, as shown, the pans embrace a major portion of the lower half of the rotor periphery.

Each rotor is provided with a plurality of inclined recesses or notches 13 arranged in a band intervening between the treatment zones. While a single band of such recesses may be used, two adjacent bands are shown and their construction and arrangement is more particularly illustrated in Figures 3 and 4. As there shown, the notches have an arcuate bottom surface 14 and the recesses in the two rows are oppositely inclined (approximately 45° to a generating element of the rotor surface as shown). The angle of inclination of the recesses is not critical and

may advantageously range between about 30° to 60°, though an approximate angle of 45° is preferred. Preferably, when two bands of recesses are used, their inclination is so related to the rotation of the rotor that adjacent recesses in the two bands have the same relationship as the flukes of an arrow head indicating the direction of rotation of the rotor as illustrated in Figure 3. However, the opposite direction may be taken or the notches of the several bands may be more or less parallel rather than opposed in inclination. Any number of bands may be used and the recesses in each band may be spaced at various distances more or less than that shown in the drawing. Where two rows of recesses are involved, the recesses in one row may be generally aligned with respect to those in the other row, as shown in Figure 3, or they may be staggered with respect thereto peripherally of the rotor. The spacing between the recesses in any given band should preferably be such as to provide intervening lands 15 of substantial thread bearing length peripherally of the rotor. Instead of arcuate bottoms to the recesses, they may be strictly flat or irregular as desired.

The strand may proceed from one treating zone to the other by way of a plurality of courses or reaches extending through the band occupied by the recesses and it may be carried solely by the lands 15 between the recesses without undergoing a substantial change in length or any substantial distortion. However, if desired, a guide 16 may be provided upon a suitable stationary arm 17 carried on the bracket 18 for displacing the strand from one treating zone to the next while preventing its making contact with the intervening recessed band of the rotor or rotors. This guide may be mounted pivotally at 19 upon the arm 17 so that it may be flipped at will into and out of operative position which is limited by the detent 20.

Figure 5 illustrates a modified pan 21 having its arcuate internal surface provided with ridges indicated by the lines 22 inclined from a direction parallel to the axis of its arcuate surface. As shown, the internal surfaces of the ridges, i. e. the edges facing the rotor, are in close proximity to the rotor and the windings about the rotor but do not touch them so that the yarn sheet on the lower half portion of the rotor periphery opposite the pan will pass through a thin layer of the processing liquid in the pan. Such ridging assists counter-current action when sufficient liquid is carried by the pan to make substantial contact with the rotor cooperating therewith. This pan may be arranged with or without the downward slope shown in connection with the pans 9, 11, and 12, of Figures 1 and 2.

The invention is adapted to the liquid treatment of a strand of any character whatsoever. Thus, it may be applied to the processing of artificial filaments or of continuous filament yarns thereof made in accordance with the viscose, cuprammonium cellulose, or any other process. It is also adaptable to the liquid treatment, coating, ornamenting, and so forth of continuous filamentary material, of artificial or natural filaments, or fibers, yarns, cords, strands, cables, ropes, and the like as well as similar constructions made of metallic wires or the like which have sufficient flexibility. While the drawing illustrates the invention as applied to a two-stage liquid process, it may be used in connection with a process involving any number of liquid-treatment stages which are axially displaced of a com-

mon thread-carrying rotor system, comprising one or more rotors adapted to advance the thread axially of the system in a helical path.

It is to be understood that changes and variations may be made without departing from the spirit and scope of the invention as defined in the appended claims.

I claim:

1. An apparatus for the treatment of a strand comprising a rotor over which the strand is adapted to proceed in a path comprising a plurality of laterally spaced convolutions and a plurality of notches each having a bottom surface arcuate in the direction of length of the notch, said notches being inclined with respect to a generating element of the rotor surface and arranged in a band about the rotor and spaced apart in a peripheral direction to provide strand-carrying lands of substantial peripheral length therebetween, thereby separating the periphery of the rotor into at least two axially spaced thread-treating zones each having a length parallel to the axis of the rotor comparatively large with respect to the notched band, and means for applying different liquids to the several strand-carrying zones.

2. In apparatus for the treatment of a strand comprising two spaced rotors adapted to receive a strand and to advance it axially thereof in a plurality of spaced elongated helical loops, means for applying different liquids to different axially spaced treating zones of at least one of the rotors, means on each of said rotors for reducing the intermingling of the different liquids applied to adjacent treating zones, and guide means arranged to extend from a support in the space between the rotors to guide the strand from the discharge end of one of said liquid treating zones to the receiving end of the next adjacent of said liquid treating zones.

3. In apparatus for the treatment of a strand comprising two spaced rotors adapted to receive a strand and to advance it axially thereof in a plurality of laterally spaced elongated loops, each rotor having a plurality of notches inclined with respect to a generating element of the rotor surface and arranged in two annular rows spaced axially of the rotor thereby separating the periphery thereof into at least two axially spaced thread-treating zones each having a length parallel to the axis of the rotor comparatively large with respect to the notched band, the notches in one of said rows being inclined in a direction opposite to the inclination of the notches in the other row, and guide means arranged to extend from a support in the space between the rotors to guide the strand from the discharge end of one of said liquid treating zones to the receiving end of the next adjacent of said liquid treating zones.

4. Apparatus for the treatment of a strand comprising a rotor over which the strand is adapted to proceed in a path comprising a plurality of laterally spaced convolutions, said rotor having at least two axially spaced treating zones, separate means for applying treating liquids to each of the two treating zones, a plurality of notches each having a bottom surface arcuate in the direction of length of the notch, said notches being inclined with respect to a generating element of the rotor surface and arranged about the rotor in a relatively narrow band disposed adjacent and between the two zones.

5. Apparatus for the treatment of a strand comprising a rotor over which the strand is

adapted to proceed in a path comprising a plurality of laterally spaced convolutions, said rotor having at least two axially spaced treating zones, separate means for applying treating liquids to each of the two treating zones, a plurality of notches each having a bottom surface arcuate in the direction of length of the notch, said notches being inclined with respect to a generating element of the rotor surface and arranged about the rotor in a relatively narrow band disposed adjacent and between the two zones and being spaced apart in a peripheral direction to provide strand-carrying lands of substantial peripheral length therebetween.

6. Apparatus as defined in claim 5 in which the notches are inclined at an angle of 30 to 60 degrees to a generating element of the surface of the rotor.

7. Apparatus as defined in claim 5 in which the notches are inclined at an angle of about 45 degrees to a generating element of the surface of the rotor.

8. Apparatus for the treatment of a strand comprising a rotor over which the strand is adapted to proceed in a path comprising a plurality of laterally spaced convolutions, said rotor having at least two axially spaced treating zones, separate means for applying treating liquids to each of the two treating zones, a plurality of notches each having a bottom surface arcuate in the direction of length of the notch, said notches being inclined with respect to a generating element of the rotor surface and arranged about the rotor in a plurality of annular rows spaced

apart axially of the rotor and disposed adjacent and between the two zones, the notches in one row being inclined in a direction opposite to the inclination of the notches in an adjacent row and the notches in each row being spaced apart in a peripheral direction to provide strand-carrying lands of substantial peripheral length therebetween.

9. Apparatus as defined in claim 8 in which the notches are inclined at an angle of 30 to 60 degrees to a generating element of the surface of the rotor.

10. Apparatus as defined in claim 8 in which the notches are inclined at an angle of about 45 degrees to a generating element of the surface of the rotor.
